UNITED STATES PATENT OFFICE.

CHARLES WILLIAM SCHUMANN, OF NEW YORK, N. Y.

DESIGN FOR A SCARF-PIN OR BROOCH.

SPECIFICATION forming part of Design No. 17,123, dated February 15, 1887.

Application filed December 13, 1886. Serial No. 921,486. Term of patent 7 years.

To all whom it may concern:

Be it known that I, CHARLES WILLIAM SCHUMANN, residing in the city, county, and State of New York, have invented and produced a new and original Design for Scarf-Pins or Brooches, of which the following is a specification, reference being had to the accompanying drawing, forming part thereof.

The drawing represents a view in perspective of a scarf or bosom pin embodying my new design.

The leading feature of my design consists of an ornament representing an old or worn and broken-down shoe, substantially as hereinafter described and claimed.

A designates the shank portion of a scarf-pin, and B its head or ornament, which is in the form of an old or worn and broken-down shoe. This ornament B, when viewed from the front of the pin, shows an old or worn shoe at full length, and so that the under side of its sole *b* and heel *c* and its upper portion, including its side *d*, which is represented as broken down, are fully exposed. The worn condition of the shoe is depicted in part by an irregular figure, *e*, in the tread or under side of the sole *b* of the shoe, extending to its side, which figure is designed to represent a hole

worn in the bottom of the sole of the shoe clear to its side. There is also a figure, *f*, on the "upper" of the shoe, at its one side, representing a patch. The old-shoe-like ornament may also have its simulating effect augmented by figures *g* on the sole or sole and heel of the shoe, representing nail-heads, and by cord-like lines or figures *h* on the upper portion of the shoe, representing a lace or lacing.

I claim—

1. The design for a scarf-pin, consisting in a pin-like shank, A, having an irregular-shaped head, B, representing an old or worn and patched broken-down shoe, exposing the under side of its sole and heel and upper portion and side thereof, as herein shown and described. 45

2. In a design for a scarf-pin or brooch, consisting of an ornament simulating an old or worn and broken-down shoe, the figure *e* on the under side of the sole, extending to the side of the shoe, and representing a hole worn in the sole of the shoe, as herein shown and described. 50

CHAS. WM. SCHUMANN.
